UNITED STATES PATENT OFFICE

JOSEPH PETER, OF LYONS, ILLINOIS, ASSIGNOR OF THIRTY PER CENT TO EUGENE L. NUSSER AND THIRTY PER CENT TO REINHOLD A. KOPP, BOTH OF CHICAGO, ILLINOIS

VACUUM PUMP

Application filed July 3, 1930. Serial No. 465,463.

This invention relates generally to a vacuum pump, and more specifically to a vacuum pump of the piston type capable of producing a high degree of vacuum.

5 The object of this invention is to provide a vacuum pump of the character described, adapted for producing a high degree of vacuum in radio tubes, electric bulbs and the like, as well as for general use, said pump being composed of few and simple parts, which may be easily and readily assembled and manufactured along lines convenient for low cost production, and which will be highly efficient for carrying out the purposes for which it is

10 designed. A further object of this invention is to provide a vacuum pump of the character described, which is adapted to be disposed for operation within a stationary casing, the operating mechanism of said pump being carried as a unit by a cover member for said stationary casing whereby the said pumping mechanism may be easily assembled or disassembled by merely removing the said cover member from the casing.

15 A still further object of this invention is to provide a vacuum pump of the piston type which is adapted to be disposed within a stationary casing for operation therein, all of said pumping mechanism being carried as a unit on a single plate member which is adapted for closing said casing, said cover member being detachably secured to said casing whereby the same may be readily removed together with all of said pump mechanism to facilitate in the assembly and disassembly of the same.

20 A still further object of the invention is to provide a vacuum pump of the piston type, all of the operating mechanism of which is carried as a unit on a single plate member which is detachably secured to a stationary casing for closing the same, said casing being provided with a supply of oil or the like whereby the said pumping mechanism will be suitably sealed, said pumping mechanism comprising an adjustably mounted cylinder the lower portion of which is suitably closed by a cylinder head provided with an opening in its central portion, said opening being closed by an

adjustable spring-pressed valve, a piston adapted for reciprocation within said cylinder, means for reciprocating said piston, openings provided in said cylinder intermediate the ends thereof for establishing communication between said cylinder and the chamber to be exhausted, said piston being adapted for opening and closing said last mentioned openings during its reciprocating movement within the cylinder.

25 A still further object of this invention is to provide, in a vacuum pump of the character described, comprising a cylinder and a piston adapted for reciprocal movement within said cylinder, of means for adjustably mounting 55 said cylinder with respect to said piston.

30 A still further object of this invention is to provide a vacuum pump of the character described, having an adjustably mounted cylinder and a piston adapted for reciprocal movement within said cylinder, said cylinder and piston being carried as a unit by a single plate member which is adapted for closing a stationary casing within which said pumping mechanism is disposed.

35 A still further object of this invention is to provide a vacuum pump of the character described, comprising a cylinder and a piston adapted for reciprocal movement within said cylinder, the lower portion of said cylinder being closed by a spring-pressed removable head which is adapted to be acted upon by the said piston to move the same for the purpose of exhausting the said cylinder.

40 A still further object of this invention is to provide a multiple stage vacuum pump of the piston type comprising a plurality of cylinders connected in series, pistons adapted for reciprocal movement within said cylinders, one of said cylinders being in communication with the chamber to be exhausted, and the other of said cylinders being in communication with said first mentioned cylinder whereby the air exhausted from the chamber will pass from the first cylinder into the second cylinder from which it will be exhausted into a supply of oil or the like.

45 With the foregoing and other objects in view, which will appear as the description 50 proceeds, the invention consists in certain

100

novel features of construction, arrangement and combination of parts, hereinafter more fully described, illustrated in the accompanying drawings and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawings a preferred embodiment thereof, from an inspection of which, when considered in connection with the following description, my invention, its mode of construction and assembly and many of its advantages should be readily understood and appreciated.

Referring to the drawings, in which the same characters of reference are employed to indicate corresponding or similar parts throughout the several figures of the drawings:

Figure 1 is a longitudinal sectional view of a vacuum pump of the piston type, embodying the principles of the present invention;

Figure 2 is a sectional view of the modified form of cylinder construction; and

Figure 3 is a sectional view of a still further modified construction showing the cylinders of a multiple stage vacuum pump connected in series.

Referring to the drawings more specifically by characters of reference, the numeral 10 designates a casing or housing constructed of any suitable material, such as cast iron or the like, and is adapted for receiving and storing a supply of oil 11, or the like, for the purpose of sealing a pumping mechanism from atmospheric pressure. A suitable stand 12 is provided to which the said casing or housing 10 is detachably secured by means of the screws 13 or the like. The stand 12 is particularly adapted for use when the said pump is to be mounted on a wooden base or the like; said stand may be dispensed with when the said casing is disposed or mounted

on a metal base, such for example as iron or the like. One side of said casing 10 is open, and is adapted to be closed by a suitable cover or plate member 14 which may be constructed of any suitable material, said

cover or plate member being detachably secured in place to the casing by means of the screws 15, there being interposed a suitable gasket 16 between said plate member and casing for suitably sealing the inside of said casing against the leakage of oil therefrom.

Adjacent the lowermost portion of said cover or plate member 14 is provided an inward extension 17 upon which extension is adjustably mounted, by means of the screws 18 and lock nuts 19, the cylinder 20. Said

cylinder is provided with a head 21 at its lower portion, said head being mounted on the screws 18 for supporting the cylinder in position within the casing 10. The head 21 is provided with a central opening 22 which opening is adapted to be closed by a valve 23, said valve being disposed within a suitable valve chamber 24 provided within the under side of the cylinder head 21.

The valve 23 comprises an annular flat valve head 25 provided intermediate the ends thereof, said valve head 25 having a suitable gasket or washer 26 provided on the upper face thereof for securely sealing the opening 22 against the passage of any oil into the valve chamber 27. The valve stem 28 of said valve 23 has the lower end thereof received for slight sliding movement within an enlarged screw-threaded member 29 which extends through a central threaded opening provided in a bracket 30, which bracket is secured to the cylinder head 21 by means of the screws 31. A nut 32 is threaded on the free end of said member 29 for locking the same in adjusted position. A suitable coil spring 33 is wound around the valve stem 28, said spring having the ends thereof bearing against the under side of the valve head 26 and the screw 29. The spring 33 is adapted to force the valve head 25 against its seat.

A piston 34 of any suitable material, is disposed within the cylinder chamber 27 and is adapted for reciprocal movement therein. If desired, a suitable piston ring 35 may be provided on said piston for insuring a tight fit between said piston and cylinder. The upper portion of the piston 34 is provided with a pair of upstanding ears or lugs 36 between which is received a connecting rod 37 to which the piston 34 is secured by means of the wrist pin 38, said wrist pin being constructed of any suitable material, such as steel or the like. The upper portion of the connecting rod 37 is provided with an eccentric 39, said cam being suitably secured by means of the taper pin 40 or the like, to the shaft 41. The size of said eccentric 39 may be varied in order to vary the stroke of the piston.

The shaft 41 is suitably journalled in bearings 42 and 43, the former being provided on the inner wall of the casing 10, and the other bearing 43 being provided in the cover plate 14. Said bearings may be constructed of any suitable material such as bronze or the like. The bearing 43 is provided with suitable packing material 44, said packing material being compressed and held in place by means of the packing nut 45 threaded on the shaft 41 in order to prevent leakage of the oil through said bearing during the operation of the pump. The free end of the shaft 41 is adapted to extend beyond the cover plate 14 and has mounted thereon and securely locked thereto a pulley 46, which is con-

nected in any suitable and wellknown manner to some suitable source of power such for example as an electric motor or the like, for driving or rotating the shaft 41.

The cylinder chamber 27 is provided intermediate the ends thereof with an inlet port or ports 47 which connect the said chamber with one end of a pipe 48, the other end of which is connected to the chamber to be exhausted. The upper end of said pipe 48 extends through the upper portion of the casing 10 and has threaded thereon a suitable nipple 49 to facilitate the connection thereto of a rubber hose or the like. The upper end of the pipe 48 is adapted to extend through a suitable packing nut 50 disposed or threaded into an opening provided in the upper wall of the casing 10, said packing nut being provided with a bored-out chamber 51 within which is adapted to be received a supply of oil for suitably sealing the opening through which the pipe 48 extends. A suitable washer 52 of packing material or the like, may be provided around the pipe 48 adjacent the packing nut 50 to prevent the leaking of any oil out of the casing when the said pump is used for pressure or in the transportation of the device.

To reinforce the casing 10, inwardly extending annular ribs 53 may be provided on the inner wall thereof, said ribs being suitably spaced from each other. The casing 10, as already stated, is adapted to receive a supply of oil, the level of which may be maintained at a point adjacent the plug 54, said plug closing the opening through which the said casing may be filled. A drain opening 55 is also provided adjacent the lower portion of said casing, said opening being closed by a suitable plug 56. A suitable opening 57 is provided in the top wall of the casing 10 to permit the escape of the air from the top portion of said casing. It will be noted that the oil level is maintained at a point sufficiently high to completely immerse the pumping unit consisting of the cylinder 20 and the piston 34.

In operation of the embodiment so far described, the openings 47 are disposed substantially at a point where the piston 34 will be at dead center on its upward stroke. After the piston has passed said openings a rush of air will be passed into the chamber 27 below the piston 34, said rush of air being caused by the production of a vacuum in said chamber because of the upward movement of the piston 34. Upon the downward stroke of the piston the said openings 47 will be sealed as soon as the piston passes over the same thus compressing the air within the chamber 27 and forcing the same out through the opening 22 by moving the valve head 26 against the action of the spring 33, said air being passed into the supply of oil and eventually escaping through the open-

ing 57 provided in the top wall of the casing 10. By repeated operations of the said piston within its chamber a very high degree of vacuum may be produced within the chamber being exhausted.

In the modified construction illustrated in Figure 2 of the drawings, the principle of operation is substantially the same as the embodiment illustrated in Figure 1, with the exception that the exhaust means for the cylinder is provided by means of a movable cylinder head which is normally spring-pressed against the bottom of the cylinder to make a substantially fluid-tight joint therewith. In this modification the cover plate 14 has detachably secured thereto, by means of the screw 60, an inwardly extending plate or bracket 17' upon which are mounted the stubs 61, said stubs being adjustably mounted on said bracket 17' and locked in any adjustable position by means of the lock nuts 62. The upper portion of said studs 61 are provided with the reduced threaded portions 63, which portions are threaded into the annular wall of the cylinder 64. The intermediate portions of said studs 61 are adapted to receive for sliding movement thereon, the cylinder head 65, said head being provided with bored-out portions 66 on the under side thereof surrounding the studs 61. A coiled spring 67 is disposed on the said intermediate portions of the studs 61, said springs surrounding said studs and having their ends bearing against the upper lock nuts 62 and the under side of the bored-out portions 66.

The upper face of the cylinder head 65 is finished off so as to provide a fluid-tight fit with the lowermost edge of the cylinder wall 64, said springs 67 normally forcing said cylinder head against the cylinder wall. The piston 34, which may be provided with the piston ring 35, is disposed within said cylinder 64 for reciprocal movement therein, said piston being actuated by the same mechanism illustrated in Figure 1. The opening 68 is provided in the side wall of the cylinder 64 intermediate the ends thereof, said opening being similar to the openings 47, and is connected with the pipe 48 which leads to the chamber to be exhausted.

It will be noted that in the operation of the modified form illustrated in Figure 2 upon the upward stroke of the piston 34 a vacuum will be created in the cylinder chamber, and as soon as the piston uncovers the opening 68 a supply of air will rush into the said chamber, which air will be compressed on the downward stroke of the piston and forced out of said chamber when said piston has engaged the cylinder head 65 and forced the same against the action of the springs 67 to the position shown in Figure 2. The movement of the cylinder head 65 away from the cylinder wall 64 will provide an escape for the

exhausting of the air from the cylinder chamber into the oil supply in the casing 10. It will also be noted that the piston 34 has a substantially fluid-tight fit within said cylinder so as to prevent the leakage of any oil into the said cylinder chamber when the piston is in the position shown in Figure 2.

In the modified construction illustrated in Figure 3 the principles of both modifications illustrated in Figures 1 and 2 are combined to provide what may be termed a two-stage vacuum pump. In this modification the specific construction of cylinder 70 is similar to that of cylinder 20 in Figure 1, and the construction of cylinder 71 is similar to that of cylinder 64 in Figure 2, the latter cylinder being provided with the loose bottom, and is connected by means of a pipe 72 with the chamber 73 into which the air from the first cylinder is adapted to be exhausted. The said chamber 73 is connected by means of a port 76 with the chamber within which the exhaust valve 23 is disposed.

The chamber 73 is provided within the bracket 30, which is secured by means of the screws 31 to the cylinder head 21, said chamber being closed at its lower end by means of a suitable plug 74 into which is threaded one end of the pipe 72, the other end of said pipe being connected to the opening 75 provided in the cylinder 71 intermediate the ends thereof. The two pumps are connected in series so that when the first stage piston is disposed above the opening 47, the second stage piston 35 will be disposed in its lowermost position for exhausting the air from the cylinder 71 into the casing 10. In order to maintain the operation of said pistons in any desired relation, the same are connected to the shaft 41 by means of a pair of cams (not shown) disposed one opposite the other.

In the operation of the modified form shown in Figure 3, upon the upward movement of the first stage piston a supply of air 45 will be drawn into the cylinder chamber 70, which supply of air will be forced into the chamber 73 by the downward movement of said piston, from which chamber it will be drawn into the cylinder 71 by the upward movement of the second stage piston. Upon the downward movement of the said second stage piston the said supply of air will be exhausted from said chamber when the piston has engaged the cylinder head 65 and moved the same against the action of the springs 67 away from the cylinder wall 71.

It will thus be noted that I have provided a vacuum pump which will not only be capable of producing a high degree of vacuum but is also constructed along lines convenient for low cost production, and which permits of ready and quick assembly and disassembly. Also, it will be noted that all of the operating mechanism is suitably mounted on the single cover member 14 whereby the same may be

readily removed for easy access to the operating parts of the pumping mechanism in order to repair or replace the same.

It is believed that my invention, its mode of construction and operation and assembly, and many of its advantages should be readily understood from the foregoing without further description, and should also be manifest that while preferred embodiments of the invention have been shown and described for illustrative purposes, the details of construction are, nevertheless, capable of wide variation within the purview of my invention as defined in the appended claims.

What I claim and desire to secure by Letters Patent of the United States is:—

1. A device of the character described, comprising a stationary casing adapted for holding a supply of oil, a removable closure member for said casing and a pumping mechanism comprising an adjustably mounted cylinder having intake and exhaust openings disposed centrally within said casing, and a piston adapted for reciprocal movement within said cylinder, said pumping mechanism being completely immersed within said supply of oil, and being carried by said closure member whereby said pumping mechanism will form a unitary structure therewith so as to permit the removal of the same from or the disposition within the casing as a single unit.

2. A device of the character described, comprising in combination a casing adapted for holding a supply of oil, a removable closure member for the side of said casing, said closure member having an inward extension upon which is adjustably mounted a cylinder provided with intake and exhaust openings, and a piston adapted for reciprocal movement within said cylinder, said piston being adapted to cover and uncover said inlet opening during its reciprocal movement, a shaft for driving said piston, a bearing for said shaft provided in said closure member, whereby said shaft, pumping mechanism and closure member will form a unitary structure to permit the removal and disposition of the same within the casing as a single unit, said cylinder and piston being completely immersed within said supply of oil.

3. A device of the character described, comprising a casing adapted for holding a supply of oil, a removable side closure member for said casing, and pumping mechanism disposed centrally within said casing and immersed within said supply of oil, said pumping mechanism comprising a cylinder having intake and exhaust openings and a piston for reciprocating movement within said cylinder, and means for driving said piston, all of said pumping mechanism and driving means being carried by said side cover member to form a unitary structure therewith, whereby the same may be removed

from or disposed within the casing as a single unit.

4. A device of the character described comprising in combination a casing adapted for holding a supply of oil, a side closure member for said casing, an inward extension provided on said side closure member and being adapted for adjustably supporting thereon a pumping mechanism including a cylinder having an inlet and exhaust opening, and a piston adapted for reciprocating movement within said cylinder, a shaft for driving said piston, said shaft being journaled in a bearing provided therefor on said side closure member, said shaft and pumping mechanism being connected to said side closure member so as to form a unitary structure therewith whereby the same may be removed from or disposed within the casing as a single unit.

20 In witness whereof I affix my signature.

JOSEPH PETER.
